ATTORNEY

WITNESS:

Gerald Hennessy

UNITED STATES PATENT OFFICE.

JOHN A. GIBSON, OF WASHINGTON, DISTRICT OF COLUMBIA.

CAN OPENER AND STOPPER.

Application filed April 18, 1925. Serial No. 24,185.

To all whom it may concern:

Be it known that I, JOHN A. GIBSON, a citizen of the United States, residing at Washington, in the District of Columbia, have invented new and useful Improvements in Can Openers and Stoppers, of which the following is a specification.

This invention relates to a combined 10 opener and stopper for cans which require two holes to be made therein before the contents can be poured therefrom, the general object of the invention being to provide a device with two points for making the holes in a can top and a pair of disks, from the 15 lower faces of which the points extend, for sealing the holes when the device is used as a stopper.

Another object of the invention is to make the device adjustable to fit different sizes of 20 cans.

This invention also consists in certain other features of construction and in the combination and arrangement of the several parts, to be hereinafter fully described, 25 illustrated in the accompanying drawings and specifically pointed out in the appended claim.

In describing my invention in detail, reference will be had to the accompanying 30 drawings wherein like characters denote like or corresponding parts throughout the several views, and in which:—

Figure 1 is a perspective view showing the device in use on a can.

Figure 2 is a side view of the device, with parts in section.

Figure 3 is a bottom plan view of the device.

In these views, 1 and 2 indicate a pair of 40 telescopic members, the outer end of each of which is curved and formed with a disk 3 and a conical point 4 which depends from the center of the disk. As will be seen, the point extends at right angles from the major 45 portion of the member so that when the device is placed on the top of the can and

pressed downwardly, the points will penetrate said top and form a pair of holes therein, through one of which the contents will pass, when the can is tilted, the other 50 hole acting as a vent for air. When the can is not being used, the device will act as a stopper for covering the holes, as the disks 3 cover the top around the holes and hold some of the liquid between themselves and 55 the top and thus form a seal to keep the contents air-tight. This will prevent deterioration of the contents and will also keep insects, dirt and the like from reaching the 60 contents.

The member 2 is formed with a socket 5 to receive a part of the member 1 and a lip 6 is pressed up from the end of member 2 to engage a groove 7 in member 1 and thus 65 guide the two members in their movement and prevent them from being separated, as the groove terminates short of the end of the member 1. Thus the device can be adjusted to place the two holes in the desired 70 position and can be used on cans of different sizes.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A device of the class described, comprising a pair of telescopic members having their outer ends bent downwardly, a disk formed on each outer end, a cone-shaped projection on the under face of each disk, the inner member having a groove therein and a lip on the outer member engaging the groove.

In testimony whereof I affix my signature.

JOHN A. GIBSON.
